(57) **CLAIM**

The ornamental design for a stalk for an automotive vehicle exterior mirror, as shown and described.

DESCRIPTION

FIG. 1 is a front perspective view of a stalk for an automotive vehicle exterior mirror, of the new design;

FIG. 2 is rear perspective view thereof;

FIG. 3 is a rear view thereof;

FIG. 4 is a front view thereof;

FIG. 5 is a top view thereof;

FIG. 6 is a side view thereof;

FIG. 7 is a side view thereof, opposite that of FIG. 6; and, FIG. 8 is a bottom view thereof.

The broken lines (including for example, the mirror, mirror housing and the internal lines at the bottom of the stalk) are for environmental illustrative purposes only and form no part of the claimed design.

1 Claim, 5 Drawing Sheets
